Primary Examiner—Catherine Tuttle*(74) Attorney, Agent, or Firm*—May M. Mowzoon; Quarles & Brady LLP**CLAIM**

The ornamental design for a packaging for fraud detection in a portable device, as shown and described.

DESCRIPTION

FIG. 1 is a front elevational view of a packaging for fraud detection in a portable device with two circular windows showing our new design;

FIG. 2 is a rear elevational view thereof; and,

FIG. 3 is a right side elevational view thereof.

The dotted lines in the figures indicate the frangible portion of the packaging forming part of the claim.
